(57) **CLAIM**

The ornamental design for a spray container, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a spray container of the present invention.

FIG. 2 is a rear view of the spray container of FIG. 1.

FIG. 3 is a top plan view of the spray container of FIG. 1.

FIG. 4 is a bottom view of the spray container of FIG. 1.

FIG. 5 is a right side view of the spray container of FIG. 1.

FIG. 6 is a left side view of the spray container of FIG. 1.

FIG. 7 is a front perspective of the spray container of FIG. 1; and,

FIG. 8 is a perspective view of the main body of the spray container of FIG. 1.

The features shown in broken lines depict environmental subject matter only and form no part of the claimed design.

The features surrounded by solid lines and alternating long and short dashes are part of the claimed design.

1 Claim, 8 Drawing Sheets
